UNITED STATES PATENT OFFICE.

LEONARD EDELMUTH AND ROBERT NAUMANN, OF NEW YORK, N. Y.,
ASSIGNORS TO N & E INK RESERVOIR CO., OF NEW YORK, N. Y.

INK-HOLDER.

SPECIFICATION forming part of Letters Patent No. 789,012, dated May 2, 1905.

Application filed July 14, 1904. Serial No. 216,524.

To all whom it may concern:

Be it known that we, LEONARD EDELMUTH and ROBERT NAUMANN, citizens of the United States, and residents of the city of New York, borough of Manhattan, in the county and State of New York, have invented a new and Improved Ink-Holder, of which the following is a full, clear, and exact description.

This invention relates particularly to improvements in devices for holding inks, the object being to provide a holder of novel construction, so arranged as to protect the ink from dirt and air, thus preserving the ink in good condition, and, further, to provide a structure that will facilitate the handling of inks substantially without loss or waste.

Other objects of the invention will appear in the general description.

We will describe an ink-holder embodying our invention and then point out the novel features in the appended claims.

Reference is to be had to the accompanying drawings, forming a part of this specification, in which similar characters of reference indicate corresponding parts in all the figures.

Figure 1 is a side elevation of an ink-holder embodying our invention. Fig. 2 is a sectional view of the ink-receptacle. Fig. 3 is a section on the line 3 3 of Fig. 2. Fig. 4 is a section on the line 4 4 of Fig. 2, and Fig. 5 is a detail showing a modification in the means for tightening the receptacle-cover.

Referring to the drawings, 5 designates the body of the ink-receptacle, consisting of any suitable metal, the said body being open at its rear end and also open at its front end. The open front end, however, is provided with a removable cover 6, in the flange portion 7 of which spirally-disposed outwardly-opening slots 8 are formed to receive pins 9 on the body. Arranged within the cover and adapted to engage with the front end of the body is a packing-ring 10, consisting of rubber or other suitable material that will form a snug joint between the parts and prevent the entrance of air. It may be here stated that the device is designed to be air-

tight; but if it is not absolutely so it will operate efficiently. Obviously by rotating the cover on the body the packing-ring will be drawn closely into contact with the parts because of the inclined walls of the slots 8. To facilitate the turning of the cover, either for applying it or for removing it, we provide it with a perforated lug 11, in which a rod or lever may be inserted. The cover is provided with an outlet-spout 12, which extends forward with a slight upward incline. This spout is rectangular in form and is normally closed by a cap 13, having spirally-disposed outwardly-opening slots 14 in its flange for receiving pins 15, extended from opposite sides of the spout. All of the corners of the spout are preferably rounded, as shown at 13^a, to permit more perfect and efficient cleaning. Arranged within the cap is a packing 16, of rubber or other suitable material, which will engage closely against the end of the spout, thus preventing the entrance of air.

Arranged on the body portion 5 is a holder for a ticket indicating the color, name, price, quality, or the like. This holder consists of guides 17, having inwardly-extended flanges under which the ticket 18 is designed to engage, and, if desired, a transparent cover 19 may be placed over the ticket. Preferably this transparent cover will consist of mica, because it is not readily broken and will easily curve to conform to the guides.

The bottom of the receptacle is arranged to slide longitudinally in the receptacle, thus forming a piston to force the ink out of the spout 12. This piston-bottom consists of metal plates 20 21, secured between which is a packing material 22, the edge of said packing material being turned over the edge of the plate 21, as clearly shown in Fig. 2.

When ink is to be ejected from the receptacle for use, the receptacle is held in a frame to be hereinafter described and having means for moving the piston. The piston-bottom is prevented from being moved outward through the open rear end of the recep-

tacle by an annular flange 23, formed at said rear end. All the corners of said flanges are rounded, as shown at 23^a, to facilitate cleaning. The rear side of the piston is provided at intervals with lugs 24, each having a plate 25 at the outer end and a rear plate 26, and thus laterally-opening pockets are formed at opposite sides of the lugs to receive wings 27, extended from a disk 28, having rotary connection with a plunger-rod 29, and as a means for turning the wings into the pockets we provide a turning-rod 30, which at its inner end is secured to the disk 28 and extends outward, terminating in an angular portion 31, forming a handpiece.

When the device is in use, the receptacle is designed to be placed in a metal frame 32 and is clamped therein by thumb-screws 33, passing through front walls of the frame and impinging against the cover of the receptacle. These thumb-screws 33 will clamp the rear end of the receptacle tightly against a shoulder 34, formed in the frame. The portion of the frame receiving the receptacle is substantially semicircular in cross-section, and the plunger-rod 29 has a bearing 35 in the rear wall of the frame, and it also has a bearing 36, attached to an arm 37, extended upward from the base 38. On one of the side bars of the frame is secured a plate 39, having a plurality of pairs of spaced lugs 40, and between the lugs of a pair a spreading knife or spatula 41 is designed to be supported, thus keeping the knives or spatulas in convenient position for use. Pivoted to lugs 42 on the base 38 is an actuating-lever 43. This lever is provided with an opening, through which the rod 29 passes, and the opposite walls of this opening are longitudinal, as indicated at 44, to receive pins 45, extended outward from the rod 29.

In Fig. 5 we have shown a modified form of devices for tightening the cover on the receptacle-body. This means consists of a bifurcated rod 46, designed to receive a pin 47 on the cover, and this rod 46 is provided with a threaded perforation to receive a screw 48, the lower end of which is swiveled in the lug 49, attached to the receptacle-body.

In the operation the ink-containing receptacle will be placed in the frame and secured as before mentioned. Then the disk 28 will be rotated by means of the rod 30 to engage the wings 27 in the pockets on the rear side of the piston-bottom, as clearly indicated in Figs. 2 and 4. When it is desired to eject ink, the cap 13 is to be removed and the piston-bottom moved forward by means of the lever 43. It is obvious that a single frame will necessarily have a considerable number of receptacles containing inks of different colors.

While we have shown a hand-lever for op-

erating the piston, it is obvious that it may be operated by other mechanical devices without departing from the spirit of our invention.

Having thus described our invention, we claim as new and desire to secure by Letters Patent—

1. In a device of the character described, an ink-receptacle comprising a body portion open at its rear end and having a removable cover for its front end, the said open rear end having an annular flange, a bottom movable in the body portion to operate as a piston, an outlet-spout extended from the cover, pins extended outward from said spout, and a cap for said spout having slots for receiving said pins.

2. In a device of the character described, an ink-receptacle comprising a body portion, a bottom movable in said body portion to serve as a piston, laterally-opening pockets on the rear side of said bottom, an actuating-rod, and means carried by said rod for engaging in said pockets upon a relative rotary motion between said means and said bottom portion.

3. In a device of the character described, an ink-receptacle comprising a body portion, a bottom movable in the body portion to serve as a piston, a flange carried by the body portion and having rounded corners, a packing carried by said bottom, means for detachably connecting an actuating device with said bottom, a cover for the receptacle, having spirally-disposed outwardly-opening slots in its flange, pins on the body for engaging in said slots, a packing-ring arranged in the cover for engaging with the front end of the receptacle-body, a spout extended from the cover and having rounded corners, pins on opposite sides of said spout, a cap for engaging over the spout, the flange of said cap being provided with spirally-disposed slots for receiving said pins, and a packing in the cap.

4. In a device of the character described, an ink-receptacle having a movable bottom forming a piston, a cover for the receptacle, means for tightening the cover on the receptacle, a supporting-frame, a plunger-rod movable in the frame and adapted for removable engagement with the movable bottom, a slotted lever mounted to swing on the frame and a pin extended from the plunger-rod into the lever-slot.

5. In a device of the character described, an ink-receptacle having a movable bottom, a frame for receiving the receptacle, means for clamping the receptacle in the frame, a plunger-rod movable in the frame, a rotary part carried by the rod and adapted for removable engagement with the movable bottom, and an actuating-lever engaging with said plunger-rod.

6. In a device of the character described, an ink-receptacle frame, a plunger-rod mounted to move longitudinally in the frame, a disk mounted to rotate on the plunger-rod, and a rod extended outward from said disk for rotating the same.

In testimony whereof we have signed our

names to this specification in the presence of two subscribing witnesses.

LEONARD EDELMUTH.
ROBERT NAUMANN.
